(57) **CLAIM**

The ornamental design for a cookware cover, as shown and described.

DESCRIPTION

FIG. 1 is a perspective view of the cookware cover installed on a piece of cookware;

FIG. 2 is a top view of the cookware cover;

FIG. 3 is a bottom view of the cookware cover;

FIG. 4 is a front elevational view of the cookware cover;

FIG. 5 is a rear elevational view of the cookware cover; and,

FIG. 6 is a side elevational view of the cookware cover, the opposite side being a mirror image thereof.

The broken lines shown in the drawings are for illustrative purposes only and form no part of the claimed design.
